(57) **CLAIM**

The ornamental design for an light fixture and mounting
therefor, as shown and described.

DESCRIPTION

FIG. 1 is a perspective view of the light fixture and mounting
therefor showing the upper, left and back portions of the
design.

FIG. 2 is a top view of the light fixture and mounting therefor.
FIG. 3 is a left side view of the light fixture and mounting
therefor, the device being symmetrical to either side of a
center vertical plane such that the left and right side views are
mirror images of one another.

FIG. 4 is a perspective view of the light fixture and mounting
therefor showing the lower, left and back portions of the
design; and,

FIG. 5 is front view of the light fixture and mounting therefor.
The elements in dashed lines do not form a part of the design.
The truncated conical cavity centrally located on the
mounting yoke seen in FIG. 4 does not form part of the design as it
cannot be viewed in use.
